(57) **CLAIM**

The ornamental design for a beverage holder, as shown and described.

DESCRIPTION

FIG. 1 is a perspective view of a first embodiment of a beverage holder, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is another perspective view thereof, shown in environmental use;

FIG. 9 is a perspective view of a second embodiment of a beverage holder, showing my new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof;

FIG. 16 is a perspective view of a third embodiment of a beverage holder, showing my new design;

FIG. 17 is a front elevational view thereof;

FIG. 18 is a rear elevational view thereof;

FIG. 19 is a right side elevational view thereof;

FIG. 20 is a left side elevational view thereof;

FIG. 21 is a top plan view thereof; and,

FIG. 22 is a bottom plan view thereof.

The broken lines in the figures illustrate portions of the beverage holder that form no part of the claimed design. The broken lines in FIG. 8 illustrate environmental subject matter only and form no part of the claimed design.

The dotted broken lines along the periphery of the rectangular border in FIGS. 1-2, 9-10, and 16-17 are included to show unclaimed stitching lines of the beverage holder and form no part of the claimed design.

1 Claim, 19 Drawing Sheets
